BY George J. Haight,
ATTORNEY.

UNITED STATES PATENT OFFICE.

CALVIN B. PATCH, OF GLENELLYN, ILLINOIS, ASSIGNOR TO WILLIAM H. MINER, OF CHAZY, NEW YORK.

DRAW-BAR AND YOKE CONNECTION.

1,286,755.

Specification of Letters Patent.

Patented Dec. 3, 1918.

Application filed January 15, 1917. Serial No. 142,398.

To all whom it may concern:

Be it known that I, CALVIN B. PATCH, a citizen of the United States, residing at Glenellyn, in the county of Dupage and State of Illinois, have invented a certain new and useful Improvement in Draw-Bar and Yoke Connections, of which the following is a full, clear, concise, and exact description, reference being had to the accompanying drawings, forming a part of this specification.

This invention relates to improvements in draw bar and yoke connections.

The object of the invention is to provide simple and efficient means for detachably connecting a standard draw bar and a yoke strap and which permits the reemployment, without modification, of old yoke straps of the riveted type.

In the drawing forming a part of this specification, Figure 1 is a longitudinal sectional view, broken away, of a draw bar and yoke showing my improvements in connection therewith. Fig. 2 is a view similar to Fig. 1, but illustrating another embodiment of the invention. Fig. 3 is a vertical, transverse sectional view of the structure illustrated in Fig. 2 and taken on the line 3-3 thereof. Fig. 4 is a sectional view of the lower portion of a draw bar butt and lower arm of a yoke strap illustrating another embodiment of my invention. And Fig. 5 is a view similar to Fig. 4 illustrating a still further embodiment of the invention.

Referring to the construction illustrated in Fig. 1, 10 denotes the butt of a standard draw bar having the usual upper and lower front shoulders 11 and 12 and the usual standardly spaced rivet holes 13-13. The front ends of the arms of the yoke are designated at 14-14, each of the same being provided with the usual standardly spaced rivet holes 15-15 alined with the rivet holes of the draw bar butt, and inwardly turned gibs or shoulders 16 that coöperate with the shoulders of the draw bar butt.

Surrounding the draw butt and the yoke strap is a rectangular band 17, the same having small perforations 18-18 in its upper wall and perforations 29-29 in its lower wall of the same size as the perforations or holes provided in the yoke strap and draw bar butt. Extending through the alined holes or perforations of the lower wall of the band, the yoke arms and into the perforations 18-18 are pins 19-19, each of the latter being reduced at their upper ends as indicated at 19^a to fit said perforations 18. The pins 19 are supported in proper position by any suitable means such as cotters 20-20, 60 which pass through suitable holes in the lower portions of said pins and alined holes in a depending lug 21 on the bottom wall of the band.

In order to disassemble the yoke and draw bar, it is apparent that the cotters 20 are first withdrawn, after which the pins may be dropped down and subsequently the band 17 slipped forwardly to permit the yoke arms to be disengaged from the draw bar. 70 In the event difficulty is experienced in removing the pins 19, the same may be forced out by means of suitable tools inserted through said perforations 18-18.

In the construction illustrated in Figs. 2 75 and 3, the draw bar and yoke are similar to the corresponding parts of the structure illustrated in Fig. 1 with the standardly spaced rivet holes. In this form, a rectangular band preferably a casting 117 is employed, the latter being provided in its lower wall with a pair of openings 40-40, through which are inserted the pair of pins 119-119. The latter are supported in position by means of a longitudinally extending cotter 80 120 that passes through suitable perforations in a pair of depending ears 121-121 formed on the lower side of the band. In this construction also, the band 117 is provided at the top with small perforations 118-118 to 85 facilitate removal of the pins 119 when necessary to employ a tool to force the latter out.

In the form illustrated in Fig. 4 the arrangement is similar to that illustrated in 95 Figs. 2 and 3, except that the pins 219-219 are supported by means of a clip 220, the clip being held in position by a pair of small cotters 220^a-220^a passing through suitable perforations in the depending ears 221-221 100 formed on the lower side of the band.

In the construction illustrated in Fig. 5, the arrangement of draw bar and yoke is the same as illustrated in the other figures. In this form, however, the pins 319-319 are inserted through the alined perforations of the yoke and draw bar before the band 317 is applied. The latter is slipped rearwardly over the butt of the draw bar, the ends of the yoke arms and the pins after the latter have 110

been assembled. The band 317 is provided at the bottom thereof with a downwardly offset wall 41 which forms a suitable seat or ledge for the lower ends of the pins 319 and thus supports the latter. In order to prevent the band from becoming displaced after the parts are assembled, a cotter 320 is employed which extends transversely of the band and is located so as to engage the rear side of the rear pin 319.

I claim:

In a device of the character described, the combination with a draw bar and yoke strap having standardly located rivet receiving holes, of a plurality of pins extending through said holes, a band encircling the

draw bar butt and the ends of the yoke strap, said band having a top wall engaged by the upper ends of said pins to thereby limit the upward movement thereof, the lower ends of said pins projecting below the lower arm of the yoke strap, the bottom of said band being formed to accommodate said projecting portions of the pins, and detachable means associated with the bottom portion of said band for retaining said pins and band in operative relation.

In witness that I claim the foregoing I have hereunto subscribed my name this 10th day of Jan., 1917.

CALVIN B. PATCH.
